UNITED STATES PATENT OFFICE

FREDERICK C. PALENSKE, OF ST. JOSEPH, MICHIGAN

RUBBER CUSHION AND INSULATING STRIP FOR REFRIGERATOR DOORS

Application filed August 10, 1931. Serial No. 556,055.

This invention relates to rubber stripping for doors of refrigerators or iceboxes or similar structures requiring tight joints and insulation between the edges of the doors and 5 the body of the structure.

Generally stated, the object of the invention is to provide a novel and improved construction and arrangement whereby a rubber stripping is provided having means for 10 forming a double seal, so to speak, having two edge portions spaced apart in position to engage one member of the structure, when the door is closed, providing a dead air space between them, whereby effective insulation 15 and an air-tight joint are provided between the door and the body of the structure.

It is also an object to provide certain details and features of construction tending to increase the general efficiency and the desirability of a rubber stripping of this particular character.

To these and other useful ends, the invention consists in matters hereinafter set forth and claimed and shown in the accompanying drawing, in which—

Fig. 1 is a front elevation of a refrigerator provided with rubber stripping between the door and the body of the structure, embodying the principles of the invention.

Fig. 2 is an enlarged horizontal detail section on line 2—2 in Fig. 1 of the drawing, showing the door in closed or substantially closed position.

Fig. 3 is a similar view, showing the door structure open.

Fig. 4 is a perspective of a section of the rubber stripping constituting the invention.

As thus illustrated, the invention comprises a rubber strip having a base portion 1 provided at one edge thereof with a flange 2, said base and flange being secured to the door 3 in any suitable or desired manner. The base 1 is provided on the face thereof with curved ribs 4 which are spaced apart and which are preferably provided with sharp edges, as shown. The portions 1 and 2 are at an angle to each other, preferably forming an obtuse angle, whereby the flange 2 will extend between the meeting edges of the door 50 and the doorway, as shown, these edges being

beveled, preferably, whereby a tight joint is formed.

When the door 3 is closed, as shown in Fig. 2 of the drawing, the ribbed portions 4 are bent or distorted as shown in Fig. 2 of the drawing, by contact thereof with the body 5 of the refrigerator structure. This provides a double seal, so to speak, as each rib 4 provides a tight joint, and in addition there is a dead air space 6 formed between the two ribs. In this way insulation is provided, in the joint between the door and the body of the structure, and a double air-tight seal is also provided, whereby there can be no interchange of relatively cold and warm air 65 inside and outside of the refrigerator. In other words, there can be no leakage around the edges of the door, tending to impair the efficiency of the refrigerator.

It will be understood, of course, that the shape of the base of the rubber stripping may be of any suitable form or character, depending upon the shape of the structure or member to which it is to be secured. But, in any event, and regardless of the shape of the base 70 or attaching portions, the stripping will have the plurality of spaced ribs on the face thereof, each rib forming an air-tight seal or joint along its edge, and the ribs together forming a dead air space between them, in the manner 75 shown and described.

It will be understood that the rubber stripping may be fastened to either the door or the body of the structure, depending upon the character thereof, without departing from 80 the spirit of the invention. It will also be seen that in the form shown one of the ribs 4 is at the edge of the base 1, while the other rib is spaced a distance therefrom. But the two ribs are curved on their outer sides, whereby the two ribs normally incline toward each other, and whereby the two ribs are bent or distorted toward each other when the door or closure is in closed position. Two ribs are shown and described, but it is obvious 85 that a plurality of ribs may be employed, involving the use of more than two ribs, without departing from the spirit of the invention. But, in any event, the formation is such 90 that dead air space is formed between the 95 ribs.

ribs when the door or closure is in closed position, with the flange 2 forming an outer tight joint, and with said ribs forming an inner tight joint.

5 What I claim as my invention is:

1. Rubber stripping for refrigerator doors, or other closures, comprising a base for attachment to a relatively movable member of the structure, formed with a portion to extend between the meeting edges of the door and doorway, said base having another portion disposed at an angle to said first mentioned portion, and a plurality of ribs on the face thereof, said ribs spaced apart to provide air space between them, and said ribs being adapted to engage another relatively movable member of the structure, when the door or closure is moved into closed position, each rib providing an air-tight joint or seal, and the ribs also providing dead air space between them when the door or closure is in closed position, thereby providing an air-tight seal and insulation in the joint between the door or closure and doorway of the body of the structure.

2. A structure as specified in claim 1, said ribs being curved toward each other, thereby being subject to distortion toward each other when the door or closure is in closed position.

3. A structure as specified in claim 1, said ribs being two in number, one rib being at the outer edge of the base, and the other rib being spaced a distance therefrom, the two ribs being curved on their outer surfaces, whereby the two ribs normally incline toward each other, and are bent or distorted toward each other when the door or closure is in closed position.

Specification signed this 3rd day of August, 1931.

FREDERICK C. PALENSKE.
